UNITED STATES PATENT OFFICE.

JULIUS BUEB, OF DESSAU, GERMANY.

MANUFACTURE OF GAS.

No. 904,043.

Specification of Letters Patent. Patented Nov. 17, 1908.

Application filed February 6, 1904. Serial No. 192,428.

To all whom it may concern:

Be it known that I, JULIUS BUEB, a subject of the German Emperor, and a resident of Dessau, Germany, have invented certain new and useful Improvements in the Manufacture of Gas, of which the following is a specification.

My invention relates to the art of making illuminating gas from coal and it consists in an improved method of distilling coal, whereby gas entirely free from naphthalene and also liquid tar are at once obtained, while the number of apparatuses and the labor required for the manufacture of such products are reduced.

It is a well-known fact, that in the art of making gas hitherto two great inconveniences are encountered. The first inconvenience is, that the gas obtained by the distillation of coal according to the methods now in use contains a considerable quantity of naphthalene, which is undesirable and objectionable, as it requires to be removed from the gas by means of a lot of apparatuses, labor and expenses, before the gas is ready for use. The second inconvenience is, that with the gas a tar is simultaneously produced, which contains a quite considerable percentage of carbon withdrawn from the gasification. This carbon is then not only withdrawn from the gasification, but also reduces the value of the tar and occasions the undesirable thickening of the tar in the recipient or condenser as is well known to the experts. Moreover this tar creates great disturbances of the work. The improved method according to my invention entirely avoids these two inconveniences, so that not only the gas leaving the retorts is free from naphthalene, but also the tar carried along with the gas is substantially free from carbon proper and so to say technically pure, it being no more a semi-liquid mass difficult to handle and occasioning disturbances, but a liquid oil at once suitable for further treatment.

I have succeeded in attaining these advantages by reason of the following considerations: Experiments carried on for many years have taught me, that the formation of the naphthalene does not necessarily follow or accompany the separation of the gas from the coal, but it only takes place as soon as the heavy hydrocarbons contained in the gas distilled from the coal are heated beyond a certain temperature, and further, that the tar rich in carbon is only produced,

if the oils forming its chief part are immediately after their formation separated from the coal from which the gas is taken off and are allowed to carry off and to take up the smoke or carbonaceous dust invariably produced in the gasification. This discovery has enabled me to find the solution of the problem. I first took up those old vertical retorts proposed at the time of the birth of the art of making gas, but never made use of, and then abolished the ancient tradition, that in the retorts there should be free spaces left for collecting the gas coming from the coal, before it is discharged into the recipient or condenser. In consequence of this the vertical retorts are arranged in a manner to be now described and illustrated in a mode of execution in the accompanying drawing, in which—

Figure 1 is a vertical longitudinal section through a gas producing apparatus on the broken line C—D in Fig. 2, and Fig. 2 is a horizontal section through the same on the line A—B in Fig. 1.

Similar letters of reference refer to similar parts in both views.

c denotes a gas generator of any known construction, *i* is an oven formed of brick-work or the like, in which a battery of vertical retorts *a a* is arranged, and *k* is a space left beneath for the introduction of trucks or wagons intended to receive and to carry off the coke produced.

The oven *i* comprises a top plate *l* and a bottom *m*, which latter rests on a bottom plate *n* supported by suitable shoulders on the internal walls of the oven *i* and an iron beam *o*. The cavity of the oven *i* is divided by several (here two) horizontal partition plates *q q* into several (here three) superposed zones. The partition plates *q q* are each provided on one side with an opening (not shown) for the fire gases passing through.

The retorts *a a* are preferably given an oval or a similar cross section and made to taper uniformly upward. Their height should be at least five times their breadth at the bottom. They are so disposed in the oven *i*, that the hot fire gases produced in the generator *c* and entering the oven *i* by means of the flues *p p* pass around the retorts *a a* in several superposed zones, in the lowermost of which the temperature is the highest. The retorts *a a* are open at the top and at the bottom and put tightly into the

bottom plate *m* *n* and the top plate *l* of the oven. The space of gasification formed in each retort *a* is provided at the top with a coal hopper (not shown) or a device *f* for the introduction of the coal, a gas-discharge *g* and a turnable cover *h* and at the bottom with a horizontal shutter *d* or similar device. In the oven compartments a convenient number of vertical partition walls *r* *r* are disposed between the internal walls of the oven and some of the adjacent retorts *a* *a*, also between certain retorts *a* *a*; so as to cause the fire gases to pass around every one of the retorts in a serpentine-like manner, as is indicated by the arrows in Fig. 2. The retorts *a* *a* are at all times kept full of coal as far as the fire gases pass around them. This apparatus is then operated in the manner, that the retorts *a* *a* are first heated up to a very high temperature (from 2400° F. to 2800° F.) and then filled up to the top or nearly so with coal while keeping them heated. The heating of the retorts is next carried on, care being taken, that the retorts *a* *a* remain filled. Owing to the great heat gas is very quickly generated from the parts of the coal in contact with the internal surfaces of the retorts, so that these parts are at once turned into compact coke, which is positively impermeable to the gas generated and forces the same to go from all points of the periphery inwardly and to pass upward through the uncoked and easily permeable coal. By the passage of the gas through the inner uncoked and cooler parts of the coal the temperature of the gas is prevented from rising beyond that limit, at which the heavy hydrocarbons of the gas would be decomposed into naphthalene. Moreover the annular crust of coke formed of the coal completely protects the gas from the contact with the intensely hot walls of the retorts. The gasification continues and the thickness of the annular crust of compact coke gradually increases inwardly, so that the diameter of the uncoked vertical core of the coal continually decreases until the remaining thin core is equally subjected to the gasification and turned into coke. The tar not finding any space for quickly separating itself from the coal is compelled to equally pass upward through the entire uncoked core of coal before leaving the retort, so that the smoke or carbonaceous dust mechanically carried off by the tar is retained and afterwards subjected with the remaining coal to the gasification. The oils forming the constituent part of the tar are incapable of gasification and escape with the gas in the shape of vapors nearly free from carbon proper to the recipient or condenser, where they are collected and present the above-mentioned appearance of the liquid oil poor in carbon.

With regard to the upwardly diminishing area of the retorts and with a view to insuring a formation as uniform as possible to the annular crust of coke, the firing of the retorts should be so conducted with the aid of conveniently arranged external flues as is for instance illustrated in the drawing, that the upper narrower part of the retorts is less heated than the lower broader part. The consequence of this arrangement of the flues and of this manner of firing is, that the thickness of the annular crust of compact coke formed on the internal surface of each retort gradually diminishes upward from the bottom to the top.

When all the coal in the retort is turned into coke, the bottom cover *d* is opened, when the coke contained in the retort will by reason of its weight fall down into a suitable truck or wagon. The bottom cover *d* is again closed and the top cover *h* is opened to introduce a fresh charge of coal into the retort *a*, after which the cover *h* is closed.

It is preferable to provide the bottom cover *d* with a conveniently shaped filling piece *e* of fire-proof material or the like, so as to keep the lowermost layer of coal on a level with the top surface of the bottom *m* and thereby to insure a complete gasification of the coal.

The results obtained by this method are most astonishing. The escaping gas does not show any trace of naphthalene. Even after passing the gas for several days through a solution of picric acid did the solution not show any turbidity. The best illuminating gas hitherto produced in any known manner, on the contrary, causes the solution of picric acid to quickly grow turbid by reason of the formation of picrate of naphthalene. Further the tar gained in the new method does not show either the characteristic black color or the semi-liquidity of the tar produced in the ordinary manufacture of illuminating gas. It is entirely new in shape and is a brown liquid oil, which never thickens in the recipient or condenser and is most easy to work for obtaining its valuable constituent parts. The illuminating gas manufactured by the new method is equal to the best illuminating gas produced by other known processes and it also yields a not inconsiderably greater outturn than hitherto, for the obvious reason, that the carbon particles, which in the old methods were taken up by the tar, are retained and subjected to the gasification in conjunction with the coal. By the new method also the number of apparatuses required for the manufacture of gas and tar is considerably reduced and moreover a great saving in labor is made. The coke obtained by the new method from the same coal is compacter and hence of higher value than the coke hitherto

produced. It is evident, that the new method affords important advantages in every respect.

The apparatus illustrated in the drawing 5 can be varied in many respects, while the method described remains substantially the same.

The word "tar" has been used in the foregoing specification to designate the by-product 10 in the present process which corresponds to the by-product, tar, in ordinary gas producing processes. In truth, however, the by-product of the present process is not tar at all, but is an oil poor in carbon, the carbonaceous matter of the ordinary gas tar having been removed as has been described.

I am well aware that vertical retorts for the manufacture of illuminating gas have been known long before the present invention, and I wish it to be understood that I do not claim broadly the use of such retorts but what I claim is a novel process which may be carried out by such retorts when operated in the way described above.

25 What I claim as my invention, and desire to secure by Letters Patent, is:—

1. The herein described process of manufacturing illuminating gas, consisting in suddenly heating the outer surface of a compact body of coal in contact with the walls of an inclosing retort to a temperature higher than that ordinarily used in producing coal gas and such as to convert the portions in contact with the walls into coke substantially impervious to gas before the interior of the body of coal is distilled and as to convert into coke the fine particles of carbon which would ordinarily be separated from coal and pass off with the tar vapors and as 40 to drive in the form of vapors the oils which ordinarily go to make tar towards the central comparatively cool portion of the body of coal, and drawing off from the central part of the body of coal and without contact 45 with the heated walls of the retort the gas and the vapor which condenses as a brown liquid oil.

2. The herein described process of manufacturing illuminating gas, consisting in suddenly heating the outer surface of a compact body of coal in contact with the walls of an inclosing retort to a temperature higher than that ordinarily used in producing coal gas and such as to convert the portions in contact with the walls into coke substantially impervious to gas before the interior of the body of coal is distilled and as to convert into coke the fine particles of carbon which would ordinarily be separated from the coal 55 and pass off with the tar vapors and as to drive in the form of vapors the oils which ordinarily go to make tar towards the central comparatively cool portion of the body of coal, and drawing off from the central

part of the body of coal and without contact 65 with the heated walls of the retort the gas and the vapor which condenses as a brown liquid oil, continuing the operation until the entire body of coal is converted into coke.

3. The herein described method of manufacturing illuminating gas, consisting in heating a retort to a high temperature, charging the heated retort with coal, the temperature of the retort at the time of admitting the charge being higher than that ordinarily 70 used in producing coal gas and such as to quickly convert that portion of the charge adjacent the retort walls throughout the heated section thereof into a coke substantially impervious to gas before the interior 75 of the body of coal is distilled and such as to convert into coke the fine particles of carbon which would ordinarily be separated from the coal and pass off with the tar vapors, and continuing the high heat until the entire 80 charge is coked, whereby the gas and tar vapor distilled from the coal is caused to pass through an interior zone of the charge having a temperature lower than that of the walls of the retort, and whereby the tar 85 leaves the retort as a vapor which condenses as a brown liquid oil, substantially as and for the purpose described.

4. The herein described method of manufacturing illuminating gas, consisting in 90 heating a vertical retort to a temperature higher than that ordinarily used in producing coal gas, filling the heated section of the retort with coal, the temperature of the retort at the time of admitting the charge being such as to quickly convert that portion 95 of the charge adjacent the retort walls throughout the heated section thereof into a coke substantially impervious to gas before the interior of the body of coal is distilled 100 and such as to convert into coke the fine particles of carbon which would ordinarily be separated from the coal and pass off with the tar vapors, and maintaining said section of the retort full while continuing the high 105 heat, whereby the gas and tar vapor distilled from the coal is caused to pass through an interior zone of the charge having a temperature lower than the walls of the retort and is prevented from coming into contact with 110 said walls, and whereby the tar leaves the retort at the top as a vapor which condenses as a brown liquid oil, substantially as and for the purpose described.

5. The herein described improvement in 115 the method of manufacturing illuminating gas, consisting in heating a retort to a temperature sufficiently high to vaporize the tar distilled from the coal, charging the retort with coal, the temperature of the retort at 120 the time of admitting the charge being higher than that ordinarily used in producing coal gas and such as to quickly convert that por-

tion of the charge adjacent the retort walls into a coke substantially impervious to gas before the interior of the body of coal is distilled and such as to convert into coke the fine particles of carbon which would ordinarily be separated from the coal and pass off with the tar vapors, and continuing the high heat until the entire charge is coked, whereby the tar vapor distilled from the coal will be caused to pass upwardly through an interior uncoked zone of the charge and tar containing a small percentage of carbon will be produced.

6. The herein described process of producing gas free from naphthalene which consists in bringing the exterior of a thick body of coal into contact with a surface heated to a temperature higher than that ordinarily used in producing coal gas, thereby producing a layer of coke substantially impervious to gas before the interior of the body of coal is distilled, and drawing off the gas and vapors produced from a portion of the coal removed from the heated surface without permitting them to come in contact with the heated surface.

7. The herein described process of producing gas free from naphthalene, which consists in bringing the exterior of a thick body of coal into contact with a surface heated to a temperature higher than that ordinarily used in producing coal gas, thereby producing a layer of coke substantially impervious to gas, and drawing off the gas and vapors produced through the cooler uncoked portions of the coal furthest removed from the heated surface before said portions have been distilled and without permitting said gas and vapors to come in contact with the heated surface.

8. The herein described method of manufacturing illuminating gas, consisting in heating a retort to a temperature higher than that ordinarily used in producing coal gas, completely filling the heated section of said retort with coal while in said heated condition, thereby quickly converting the portion of the charge adjacent the walls into a coke substantially impervious to gas before the in-

terior of the body of coal is distilled, continuing the high heat until the entire charge is coked whereby the gas and vapor pass to the comparatively cool central zone of the coal, and drawing off the gas and vapor from said central zone without contact with the heated walls.

9. The herein described method of manufacturing illuminating gas, consisting in heating a retort to a temperature higher than that ordinarily used in producing coal gas, completely filling the heated section of said retort with coal while in said heated condition, thereby quickly converting the portion of the charge adjacent the walls into a coke substantially impervious to gas before the interior of the body of coal is distilled, continuing the high heat until the entire charge is coked, whereby the gas and vapor pass to the comparatively cool central zone of the coal, so distributing the heat as to finish the coking operating at all points along the height of the furnace at substantially the same time, and drawing off the gas and vapor from said central zone without contact with the heated walls.

10. The herein described process of manufacturing illuminating gas, consisting in suddenly heating the outer surface of a vertical column of coal to such a temperature as to convert the said surface into a layer of coke substantially impervious to gas before the interior of the body of coal is distilled continuing the heat until the entire column is converted into coke, applying the heat in such a way that the coking operation will be first completed at the bottom of the column and will gradually extend to the top, and drawing off the gas and vapors from the central part of the column at the top without contact with highly heated surfaces.

In testimony whereof I have signed my name to this specification in the presence of two subscribing witnesses.

JULIUS BUEB.
